UNITED STATES PATENT OFFICE.

HARRY EVANS INK, OF ST. LOUIS, MISSOURI, ASSIGNOR TO RICE-STIX DRY GOODS COMPANY, OF ST. LOUIS, MISSOURI, A CORPORATION OF MISSOURI.

MERCHANDISE-HOLDER.

1,159,943.

Specification of Letters Patent.

Patented Nov. 9, 1915.

Application filed December 19, 1914. Serial No. 878,170.

To all whom it may concern:

Be it known that I, HARRY EVANS INK, a citizen of the United States, and a resident of the city of St. Louis and State of Missouri, have invented a new and useful Improvement in Merchandise - Holders, of which the following is a specification.

My invention relates to boxes or receptacles for packing, shipping and displaying neckties, cravats, gloves, belts and similar articles.

One of the objects of the invention is a combined shipping receptacle and display holder which will protect the contents during shipment, and which can be easily arranged to display the contents artistically.

A further object is a shipping and storing receptacle which can be cheaply manufactured and which can be used repeatedly and for various sizes and shapes of goods.

Further objects and advantages of the invention will be more fully set forth herein-after.

The invention consists in the device illustrated in the accompanying drawing, and in the parts, and in the arrangements and combinations of parts, which are more fully set forth herein-after; and what the invention comprises is particularly described in the appended claims.

In the accompanying drawing, which forms part of this specification and in which like reference characters refer to like parts in the several views, Figure 1 is a front and top view of a necktie box embodying the invention, showing one way of displaying neckties contained therein; Fig. 2 is a longitudinal section through the box shown in Fig. 1, showing the box and its contents as packed for shipment; and Fig. 3 is an isometric view of the box, showing how it may be equipped and arranged for displaying merchandise, the merchandise not being shown.

The device shown in the drawing comprises a shallow rectangular box 1 of cardboard or similar material, which has a telescoping cover 2. Extending longitudinally of the box 1 is a strip 3 of relatively stiff cardboard which is fastened at one end by eyelets 4, or other suitable fastening means, to the bottom of the box 1 near one end thereof. A prop or extension 5 is hinged to the free end of the strip 3. The prop 5 is preferably made from a strip longer than

the box by bending under a portion thereof. The required flexibility of the joint between the prop 5 and strip 3 is obtained by lightly scoring one of the faces of the long strip transversely of its length. The prop 5 is arranged to fold under the strip 3 and lay flatwise on the bottom of the box 1. The articles of merchandise, which in this instance are shown as neckties 6, are secured to the strip 3, preferably by a paper band 7 which may be slidable on said strip. A sheet of tissue paper 8, or other suitable material, longer and wider than the box, is arranged in the box underneath the strip 3, said strip holding the paper in place. The sheet of paper 8 has a notch 9 in one edge thereof which fits around the end portion of the strip 3 which is fastened to the box (see Fig. 3), thus enabling the paper to be removed and replaced by fresh paper as desired. A piece of cardboard 10, of a size to fit loosely in the box, is preferably provided for supporting the paper 8 in displaying the contents of the box.

In packing the articles in the box for shipment, the band 7, which is commonly used to hold such articles as neckties in a bundle, is applied around the articles and the strip 3, and between it and the prop 5. The strip 3 and the articles are suitably folded to fit into the box, as by doubling the ends under, if necessary, as shown in Fig. 2. The paper 8 is folded over the articles, and the cover 2 is put on the box. The strip 3 and the band 7 hold the articles securely in place in the box and keep them from moving or being crumpled or injured during shipment.

The box and its contents may be easily arranged by the merchant in different ways to display the merchandise attractively. In one arrangement, shown in Fig. 1, the cover 2 of the box is removed, the paper is unfolded, the strip 3 is lifted up, and the ties are unfolded and spread out. The piece of cardboard 10 is slipped out and rested over the end of the box to form a support for the paper, which thus forms a background. If desired, the box can be tipped up to show the articles to a better advantage, as they are securely held in place in the box by the strip 3 and the band 7. Another arrangement for displaying the articles in the box is shown in Fig. 3, wherein the strip 3 is raised from the bottom of the box and

the prop 5 is unfolded to hold up said strip. The piece of cardboard 10 is arranged as before, and the paper 8 is spread out over it. The prop 5 rests on the paper where it is supported by the cardboard. The box can be tipped up or laid flat as desired for display purposes without disarranging the contents.

The combined shipping receptacle and display device hereinbefore described enables the articles contained therein to be shipped without injury and to be displayed artistically without the use of pins, supports or devices other than those contained in the box. For the purpose of a packing box, the above described receptacle can be more cheaply manufactured than those containing built-up forms or compartments, and it can be as easily packed. The paper 8 which is used to wrap the articles in the box and to form the background for displaying them can be easily replaced when soiled, thus enabling the box to be used repeatedly for display purposes.

The invention is not restricted to the precise forms and arrangements shown and described, nor to packaging and displaying merchandise, nor to use solely in connection with the articles referred to above.

What I claim is:

1. A combined shipping and display receptacle comprising a long narrow box, a strip of cardboard narrower than said box consisting of two portions of unequal length hinged together and folded flatwise, the extremity of the longer one of said portions being securely fastened flatwise to the bottom of said box near one end thereof, the other of said portions being folded under said first-mentioned portion when said box is closed, and free to unfold to support said portion in an inclined position relatively to

the bottom of said box, and means on said strip for securing articles thereto whereby they are supported and held in alinement in said box in both the flatwise and the inclined positions of said strip.

2. A combined shipping and display receptacle comprising a long narrow flat box having a removable top or cover, a strip of cardboard longer than said box and secured flatwise at one end to the bottom of said box near one end thereof, the free end portion of said strip being doubled under the body portion of said strip near the other end of said box, and a band or loop for securing articles to the body portion of said strip near its unsecured end, whereby ties and the like may be wrapped around said free end portion and secured to said body portion for shipping and display purposes.

3. A combined shipping and display receptacle comprising a box having a sheet of paper arranged in its bottom, in combination with a strip of relatively stiff material arranged lengthwise of said box over said paper and secured to said box near one end and free at its other end, and means for securing articles to said strip, said sheet of paper being larger than said box and adapted to be folded over said strip to inclose articles secured thereto, said paper having one edge notched to embrace the fixed end of said strip and being removably secured in place by said strip whereby when said paper is unfolded it will be retained in display position beneath articles secured on said strip but may be readily replaced when soiled.

Signed at St. Louis, Missouri, this 17th day of December, 1914.

HARRY EVANS INK.
